G. I. DANLY.
DRUM AND CYMBAL BEATER.
APPLICATION FILED DEC. 23, 1921.

1,437,173.

Patented Nov. 28, 1922.

INVENTOR:
GEORGE I. DANLY,

BY *Robert Burns*, ATTORNEY.

UNITED STATES PATENT OFFICE.

GEORGE I. DANLY, OF CHICAGO, ILLINOIS, ASSIGNOR TO LUDWIG & LUDWIG, INC., OF CHICAGO, ILLINOIS, A CORPORATION OF ILLINOIS.

DRUM AND CYMBAL BEATER.

Application filed December 23, 1921. Serial No. 594,378.

To all whom it may concern:

Be it known that I, GEORGE I. DANLY, a citizen of the United States, residing at Chicago, in the county of Cook and State of Illinois, have invented certain new and useful Improvements in Drum and Cymbal Beaters, of which the following is a specification.

This invention relates to drum and cymbal beaters of the pedal actuated type, such as forms the subject matter of Patent No. 1,386,605 of August 9, 1921, to Robert C. Danly. And the present improvement has for its objects:—

15 To provide a simple and durable structural formation and association of parts whereby an efficient mechanism is produced in an economical manner.

20 To provide an effective means for connecting the cymbal beater arm to the drum beater arm in a manner adapted to permit of a ready swinging of the cymbal beater arm from an active to an in-active position, and with which said cymbal beater arm is 25 effectively held in either position to which it may be moved by the operator, all as will hereinafter more fully appear.

In the accompanying drawing:—

Fig. 1, is a side elevation, illustrating in 30 full lines, the parts in the normal retracted position, and in dotted lines the parts in their striking position.

Fig. 2, is a rear end elevation.

Fig. 3, is a top view of the cymbal beater 35 arm, showing its connection to the drum beater arm, which latter is shown in section.

Fig. 4, is an enlarged detail horizontal section on line 4—4, Fig. 1.

Fig. 5, is an enlarged detail vertical section on line 5—5, Fig. 4.

Like reference numerals indicate like parts in the several views.

Referring to the drawing, 1 designates the supporting base or floor member of the 45 mechanism, comprising upper and lower strips of plate metal fixedly secured together at their midlength, with the end of one strip formed with a transverse loop or pivot eye 2, and with the opposite ends of the strips 50 arranged in separated relation to form a pair of spaced resilient clamping jaws 3 adapted to engage the usual hoop of a drum and have clamping engagement therewith through the instrumentality of a clamping

screw 4 passing through intermediate parts 55 of said jaws, as shown.

5 designates the carrying arm of the drum beater head 6, of an angular shape, and which in the preferred construction is formed of rod metal bent to an angular 60 shape to provide a straight stem portion 7 carrying on its free end the aforesaid beater head 6, and a pedal portion 8 of a closed loop shape having a triangular form, with the transverse member 9 of said loop having a straight form and adapted to fit and have pivotal movement in the pivot eye 2 of the base member 1. In the described formation of parts the triangular loop shape of the pedal portion 8 is adapted to provide 70 a wide and ample rest for the foot of the operator in actuating the present mechanism.

10 designates a curved spring of plate metal secured to the base member 1 near the pivot eye 2 thereof, with its free end 75 bearing against the under side of the pedal portion 8 to yieldingly hold the beater parts in their normal retracted position. The described formation and arrangement of the spring 10 and associated parts is adapted to 80 provide an efficient and very easy operation in actual use, in that only a slight resistance is offered to the initial movement of the beater carrying arms, with such resistance progressively increasing as the movement 85 progresses due to the shift of the fulcrum of the spring along the base 1 as the flexure of the spring increases.

11 designates the carrying arm of a cymbal beater head, formed of plate metal, and 90 having at one end a holding eye 11' for the usual adjustable stem of a cymbal beater head, with the other end bearing against the rod portion 7 of the carrying arm of the drum beater head, with such end formed 95 with curved channels 12 and 13 in cross relation to each other for alternate holding engagement with the adjacent curved surface of said rod portion 7. Said end of the arm is also formed with an orifice central of said 100 cross channels 12, 13 for pivotal attachment to said rod portion by means as follows:—

14 designates a fixed stem or pin extending laterally from the aforesaid rod portion 7, provided with an outer head 15 forming an 105 abutment for the bearing washer or collar 16 of a spring 17 arranged between the collar 16 and the outer face of the arm 11 and

adapted to yieldingly force said arm against the rod 7 and retain one or the other of the curved channels 12, 13, in holding engagement with the rod 7, as the carrying arm 11 of the cymbal beater head is manually moved to an active position at right angles to the rod or stem 7, or to an active position in parallel relation to said rod or stem.

Having thus fully described my invention, 10 what I claim as new and desire to secure by Letters Patent, is:

1. In a drum beater mechanism, the combination of a base member formed of upper and lower strips of plate metal and having 15 an integral transverse pivot eye at one end and a pair of integral clamping jaws at the other end, a clamping screw associated with said jaws, a drum beater arm having an angular shape and having pivotal engagement in the pivot eye of the base member, and a plate metal spring of a curved form attached at one end to the base member adjacent to its pivot eye with the free end of the spring having bearing against the under 25 side of the beater carrying arm.

2. In a drum beater mechanism, the combination of a base member formed of upper and lower strips of plate metal and having an integral transverse pivot eye at one end 30 and a pair of integral clamping jaws at the other end, a clamping screw associated with said jaws, a drum beater arm having an angular shape and formed of rod metal with its pedal portion formed by a triangular loop 35 of the rod material, said loop having a straight transverse portion for pivotal engagement in the pivot eye of the base member, and a plate metal spring of a curved form attached at one end to the base member

adjacent to its pivot eye with the free end of 40 the spring having bearing against the underside of said triangular loop.

3. In a combined drum and cymbal beater mechanism, the combination of a carrying stem of a drum beater head, a plate metal 45 arm having at one end attaching means for a cymbal beater head and at its other end having crossed curved channels and a central pivot orifice, a fixed lateral stem secured to the carrying stem of the drum beater head 50 engaging said pivot orifice, and a spring associated with said lateral stem and adapted to force the carrying arm of the cymbal beater head towards the carrying stem of the drum beater head to maintain one or the 55 other of the crossed channels in engagement with the carrying stem of the drum beater head.

4. In a combined drum and cymbal beater mechanism, the combination of a carrying stem of a drum beater head, a plate metal 60 arm having at one end attaching means for a cymbal beater head and at its other end having crossed curved channels and a central pivot orifice, a headed lateral stem secured 65 to the carrying stem of the drum beater head engaging said pivot orifice, a bearing collar arranged on said lateral stem and a coiled spring encircling said lateral stem and interposed between said collar and said arm 70 and adapted to force said arm towards the stem of the drum beater head to maintain one or the other of the crossed channels in engagement with said stem of the drum beater head.

Signed at Chicago, Illinois this 19th day of December, 1921.

GEORGE I. DANLY.
